UNITED STATES PATENT OFFICE.

ANGUS R. GROSS, OF BALTIMORE, MARYLAND.

DESIGN FOR A COWL-LIGHT FOR AUTOMOBILES, &c.

59,213.

Specification for Design.

Patented Oct. 4, 1921.

Application filed February 18, 1921. Serial No. 446,172. Term of patent 14 years.

To all whom it may concern:

Be it known that I, ANGUS R. GROSS, a citizen of the United States, residing at Baltimore, State of Maryland, have invented a new, original, and ornamental Design for a Cowl-Light for Automobiles, &c., as shown in the accompanying drawing, forming part of this specification.

In said drawings:—Figure 1 is a side view of the cowl light. Fig. 2 is a front end view thereof. Fig. 3 is a rear end view thereof.

The design consists of an approximately

projectile shaped body portion A, which is preferably polygonal in cross section and it has a transparent light or jewel in its front end and its rear end tapers to a polygonal sided point, and the under side of this body has a depending parti-cylindric lug or T portion D by which it may be attached to a suitable support on the cowl.

I claim—

The ornamental design for a cowl light for automobiles, etc., substantially as shown and described.

ANGUS R. GROSS.
